UNITED STATES PATENT OFFICE

WILLIAM A. RINGLER, OF PHILADELPHIA, PENNSYLVANIA

LOOSE-LEAF BINDER

Application filed August 19, 1925. Serial No. 51,109.

My invention comprehends a novel construction and arrangement of a loose leaf binder which consists of but three parts, namely: a fixed part adapted to be connected 5 to a cover, a filler carrying member movably connected with said fixed part, and a slide which is adapted to lock the filler carrying member with respect to said fixed part.

10 Each of these parts are formed from an integral piece of material, so that the device can be very economically manufactured.

It further comprehends a novel construction of a fixed member, a novel construction 15 of a slide and a novel construction of a filler carrying member.

Other novel features of construction and advantage will hereinafter more clearly appear in the detailed description and the appended claim.

20 For the purpose of illustrating the invention, I have shown in the accompanying drawing a typical embodiment of it, which, in practice will give reliable and satisfactory 25 results. It is, however, to be understood that this embodiment is typical only and that the various instrumentalities of which my invention consists can be variously arranged and organized, and that the invention is not 30 limited to the precise arrangement and organization of these instrumentalities as herein set forth.

Figure 1 is a plan view of a memorandum book, having a loose leaf binder embodying 35 my invention.

Figure 2 is an enlarged detail of a portion of the construction seen in Figure 1.

Figure 3 is a plan view of the construction seen in Figure 2, but showing the hook in 40 its unlocked position.

Figure 4 is a section on line 4—4 of Figure 1.

Figure 5 is a section on line 5—5 of Figure 1.

45 Figure 6 is a section on line 6—6 of Figure 5.

Figure 7 is a plan view of the fixed portion of the binder.

50 Figure 8 is a perspective view of the hook member which carries the filler.

Figure 9 is a perspective view showing a portion of the slide and casing.

Figure 10 is a perspective view of another form of hook member embodying my invention.

55 Figure 11 is a sectional view of an embodiment of my invention employing the hook member seen in Figure 10.

Similar numerals of reference indicate 60 corresponding parts.

Referring to the drawings:

1 designates the base member of a loose leaf binder, embodying my invention, and 2 designates a filler carrying member which is hinged to the fixed member in a novel manner and interlocks therewith by means of a slide 3. The binder is adapted to be connected to a cover 4. The fixed member, the movable member and the slide are each preferably formed from a single piece of material. The fixed member is formed from sheet material which is folded to form a rectangular tube with a top 5 and the bottom 6, connected by the side 7. The top 5 is provided with the slots 8 which are enlarged as at 9, see Figure 3. The top is also provided with the openings 10. The top is deflected downwardly as at 11, see Figure 5, and it merges into the intermediate portion 12, so that a space is formed between the top 75 5 and the intermediate portion 12 to receive the slide 3, which is also formed of a single piece of sheet material which is deflected upon itself to form the top member 13 and the bottom member 14.

80 85 It will be understood from the foregoing that the fixed member is substantially rectangular in cross section, with the free edges 12 and 6 overlapping.

At one end the slide is deflected as at 15 90 to form a grasping handle, and the slide in proximity to its end is apertured, as at 16, and it is provided with bayonet types of slots 17 which are preferably of the same contour as the slots 8 in the top 5 of the fixed member.

95 The ends of the fixed member 5 are bent downwardly and inwardly and have the terminals 18 which pass through the cover 4 and the bottom portion 6 of the fixed mem- 100

ber 5 in order to secure the binder to the cover. The purpose of the openings 16 in the slide and the registering openings 19 in the fixed member 5 is to enable one to insert a tool through such openings to clinch the ends 18 of the fixed member 5, see Figure 4.

The filler carrying member 2 is formed from a single piece of material and as illustrated, it is bent upon itself to form the filler retaining loops 20, and it is also deflected upon itself to form the hooks 21, which may be located at any desired point in the longitudinal length of the filler carrying member 2, and, as illustrated, each loop has in proximity to it one of the hooks 21.

Instead of forming the hook 21 from the longitudinal stretch of the filler carrying member, a filler carrying member 22 may be employed in which the loop 23 terminates in a horizontally extending hook 24, which, as seen in Figure 11, is locked and unlocked by the slide 3, and the openings 25 which correspond to the openings 8 and 9 are located in the opposite side of the casing from that seen in Figure 7.

In the operation, when the slide 3 is moved outwardly, it will be apparent that the hooks 21 will be brought into register with the enlarged portion 9 of the openings 8 and with the enlarged portion of the openings of the slots 17, so that the filler carrying member can be swung backwardly and the leaves of the filler inserted or removed as may be desired.

The operation of the filler carrying member seen in Figures 10 and 11 is similar to that already described, since when the slide is moved outwardly the hooks 24 will be unlocked and when said slide is moved inwardly the hooks 24 will be locked.

The fixed member or casing can be very cheaply manufactured from sheet material, and, at one end, the top is bent downwardly to form the means for securing it to the cover, and, at the opposite end, one of the bottom laterally extending portions is bent downwardly to form the means at such end for securing the fixed member to the cover.

The slide is formed from a single piece of material which is transversely folded upon itself, the bottom being of less width than the top. The slide is contained within the fixed member so that when the parts are assembled the longitudinal stretch of the filler carrying member will be retained in hinged relationship with respect to the fixed member or casing which carries it.

It will be apparent that since each of the three parts are formed from a single piece of material that my present construction of loose leaf binder can be economically manufactured, and, at the same time, it will be durable and reliable in practice. The dif-

ferent openings of the slots in the slide and the casing can be formed at the same time the blank is cut from sheet material.

It will now be apparent that I have devised a new and useful loose leaf binder which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:

A loose leaf binder, comprising a base member folded to form a rectangular tube, a filler carrying member hinged to said base member, provided with filler retaining loops and with a hook, and a slide in said tubular member cooperating with said hook to secure said loops in their locked or unlocked position, said base having deflected portions to secure it to its cover, and said base and slide having registering openings to receive a tool to clinch the ends of such portions.
